Wirt S. Quigley Inventor
By his Attorney D. Van Rossmich

UNITED STATES PATENT OFFICE.

WIRT S. QUIGLEY, OF NEW YORK, N. Y., ASSIGNOR TO QUIGLEY FURNACE AND FOUNDRY CO., A CORPORATION OF MASSACHUSETTS.

PULVERIZED-FUEL BURNER.

1,191,225.

Specification of Letters Patent. Patented July 18, 1916.

Application filed October 8, 1913. Serial No. 794,038.

To all whom it may concern:

Be it known that I, WIRT S. QUIGLEY, a citizen of the United States of America, residing at New York city, borough of Manhattan, county and State of New York, have invented certain new and useful Improvements in Pulverized-Fuel Burners, of which the following is a specification.

My invention relates to apparatus for 10 burning finely divided fuel, such as pulverized coal and comprises a special form of feeding device for delivering such pulverized fuel to the combustion chamber of a furnace.

In apparatus of this kind it is customary 15 to employ currents of air to force or blow the finely divided fuel into the combustion chamber of the furnace, the air being under pressure and serving to bodily transport the fine particles of coal or other solid fuel, to 20 supply the necessary oxygen for combustion and to thoroughly mix the two together so as to facilitate combustion.

In applying apparatus of this kind to furnaces already in operation, or in adapting it 25 to the varying conditions met with in installing new furnaces, many different designs have been heretofore required according to the relative positions of the combustion chamber, the air compressor, the fuel 30 supply, etc.

My invention comprises a single, stand- 35 ardized form of apparatus, made from a single set of patterns, but the parts of which are so connected as to be adjustable to meet all conditions, thereby producing a universal fuel feeding apparatus which may be manufactured cheaply and in quantity and applied to any furnace, whatever the relative positions of the air and fuel connections ren- 40 dered necessary by other considerations.

The best form of apparatus, with one modification, embodying my invention, at present known to me, is illustrated in the accompanying two sheets of drawings, in 45 which—

Figure 1 is a plan view with parts broken away, or shown in section, showing one position, Fig. 2 is a side elevation, Fig. 3 is a rear elevation, and Fig. 4 is a view similar 50 to Fig. 1, showing a modification.

Throughout the drawings, like reference characters indicate like parts.

1, represents the wall of the combustion chamber which is pierced at 31, for the fuel 55 inlet. 2, is a collar plate fastened to the ex-

terior of the wall around opening 1, as by bolts 3, 3. Plate 2 has an exterior collar or flange 4, into which the inner end of the main section 5 of the air tube fits. 7, is an exterior, circumferential groove on 5, near its inner end, within collar 4, and 6, 6, are radial setscrews in collar 4, engaging groove 7. Tube section 5, has a radial inlet 8, provided with stuffing box 9, packing 28, and gland 29, held in position by bolts 30, 30, or other fastening means, and also has a bell mouthed flange 10, on its outer end provided with radial setscrews 13, 13, which fit into circumferential groove 12, on the end of air tube elbow 11, where it is inserted into flange 10. Stuffing box 9, is preferably mounted on a plate 32, which is fastened to section 5, by bolts 33, 33, and covers opening 8.

A peep hole 14, with pane 15, of mica or other transparent material is provided in elbow 11, preferably in line with the axis of main section 5, and protected by shutter 40, which may be pivoted at 41, so that it may be swung aside when desired.

16, is a fuel nozzle connected by T-casting 80 17, to fuel supply pipe 18. The other end of the T is plugged by nut 34.

In assembling the parts composing this form of my invention, the plate 2, is bolted into position, the tube section 5, inserted 85 into the collar 4, and fastened into position by setscrews 6, 6, engaging groove 7. The fuel supply pipe 8, with the nozzle 16, and the stuffing box 9, mounted thereon is then inserted through the radial opening 8, and the plate 32 fastened into position to cover said opening. The nozzle 16, then being adjusted in position and properly centered, the elbow 11, is inserted in flange 10, and fastened therein by setscrews 13, 13, en- 90 gaging groove 12.

In the modification shown in Fig. 4, the main air tube section 19, has an inclined side inlet 20, with coupling 21, bolted thereto. This coupling carries stuffing box 22, 100 similar in construction to stuffing box 9. The fuel pipe 23, is curved to pass through this stuffing box and have its nozzle 24, centered in air tube section 19, and with reference to furnace opening 31. The fuel pipe 23, may have a roughened exterior portion 25, adapted to be grasped by the packing washer 26, to prevent said tube slipping in or out.

In operation the pulverized coal or other 110

fuel is fed in through the fuel pipe and through the fuel nozzle by a current of air, or other means, and after leaving the nozzle it is intermingled with the larger quantity 5 of air needed for complete combustion supplied by the air tube. The peep hole and opening in elbow 11, serve as means for observing the combustion, and for affording access to the fuel nozzle for adjustment, 10 or cleaning, after removing plug 34.

The advantages of the invention reside in the fact that either form may be made in standard sizes and stock quantities, and fitted to any furnace of the proper capacity, 15 no matter what the location of the apparatus with reference to the fuel and air supply mains. Furthermore, the apparatus may be applied, dismantled, or readjusted to suit changed conditions with the greatest 20 facility, by merely loosening the setscrews, turning the different sections as desired, and retightening the set screws. The peep hole, being in line with the nozzle and furnace opening, the condition of combustion being 25 produced can be readily observed at any time.

Various changes could be made in the details of construction shown and described without departing from the principle of my 30 invention or materially decreasing its resultant advantages so long as the general arrangement hereinbefore set out, by which the main elements are rotatably secured one to another, is preserved.

35 Having described my invention, I claim:
1. A pulverized fuel feeding device composed of standard elements capable of adjustment to suit different angles of connection to air-and-fuel-supply pipes and supplemental-air-supply pipes having in combination a flanged collar plate adapted to be fastened to a furnace wall, radial set screws in said collar, a main tubular sec-

tion adapted to be inserted in said collar and grasped by said setscrews, provided 45 with a side opening and with a bell mouthed flange at its outer end, radial setscrews in said bell mouthed flange, an elbow section adapted to be inserted in said bell mouthed flange and grasped by said setscrews, and a 50 fuel feeding pipe passing through said side opening.

2. A pulverized fuel feeding device composed of standard elements capable of adjustment to suit different angles of connection to air-and-fuel-supply pipes and supplemental-air-supply pipes having in combination a flanged collar plate adapted to be fastened to a furnace wall, radial set screws in said collar, a main tubular section 55 adapted to be inserted in said collar and grasped by said setscrews, provided with a side opening and with a bell mouthed flange at its outer end, radial setscrews in said bell mouthed flange, an elbow section 60 adapted to be inserted in said bell mouthed flange and grasped by said setscrews, and a fuel feeding pipe passing through said side opening, said elbow section being provided with a peephole in line with the interior of 70 the main section.

3. A pulverized fuel feeding device having in combination a main tubular section with a side inlet, means for rotatably securing said section to a furnace wall, a 75 plate detachably fastened to said tubular section over said side opening, a stuffing box carried by said plate, a fuel feeding pipe passing through said stuffing box, an air supply connection and means for rotatably 80 securing the same to the rear end of the main tubular section.

WIRT S. QUIGLEY.
